The ornamental design for a dispensing cap, as shown and described.

DESCRIPTION

FIG. 1 is an isometric view of a top, front, and left side of an ornamental design for a dispensing cap;

FIG. 2 is a front elevational view of the dispensing cap of FIG. 1;

FIG. 3 is a rear elevational view of the dispensing cap of FIG. 1;

FIG. 4 is a left side elevational view of the dispensing cap of FIG. 1, the right side elevational view being a mirror image thereof;

FIG. 5 is a top plan view of the dispensing cap of FIG. 1;

FIG. 6 is an isometric view of a top, front, and left side of the dispensing cap of FIG. 1, wherein the lid is shown in a closed position;

FIG. 7 is an isometric view of a top, front, and left side of a second embodiment of an ornamental design for a dispensing cap;

FIG. 8 is a front elevational view of the dispensing cap of FIG. 7;

FIG. 9 is a rear elevational view of the dispensing cap of FIG. 7;

FIG. 10 is a left side elevational view of the dispensing cap of FIG. 7, the right side elevational view being a mirror image thereof;

FIG. 11 is a top plan view of the dispensing cap of FIG. 7;

FIG. 12 is an isometric view of a top, front, and left side of the dispensing cap of FIG. 7, wherein the lid is shown in a closed position;

FIG. 13 is an isometric view of a top, front, and left side of a third embodiment of an ornamental design for a dispensing cap;

FIG. 14 is a front elevational view of the dispensing cap of FIG. 13;

FIG. 15 is a rear elevational view of the dispensing cap of FIG. 13;

FIG. 16 is a left side elevational view of the dispensing cap of FIG. 13, the right side elevational view being a mirror image thereof; and,

FIG. 17 is a top plan view of the dispensing cap of FIG. 13. The broken lines are for the purpose of illustrating environmental structure and form no part of the claimed design. Further, the bottom views form no part of the claimed design.
